UNITED STATES PATENT OFFICE

157,693

NONSKID TIRE

Paul H. Long, Ravenna, Nebr.

Application January 12, 1948, Serial No. 143,661

Term of patent 3½ years

(Cl. D90—20)

To all whom it may concern:

Be it known that I, Paul H. Long, a citizen of the United States, residing at Ravenna, in the county of Buffalo and State of Nebraska, have invented a new, original, and ornamental Design for Nonskid Tire, of which the following is a specification, reference being had to the accompanying drawing, forming part thereof.

Figure 1 is a perspective view of a nonskid tire, showing my new design;

Figure 2 is a fragmentary plan view of the tread portion thereof; and

Figure 3 is a fragmentary sectional view taken on the line 3—3 of the Figure 2.

The dominant features of my design reside in the portions shown in full lines.

I claim:

The ornamental design for a nonskid tire, as shown and described.

PAUL H. LONG.
